DRAFT AND BUFFER GEARING

Glenn E. Edmunds, Columbus, Ohio, assignor to
 The Bonney-Floyd Company, Columbus, Ohio,
 a corporation of Ohio

Application January 27, 1934, Serial No. 708,679
 Renewed September 4, 1936

13 Claims. (Cl. 213—9)

The present invention relates to draft and buffer gearing. While the gearing of the invention is of general application, it is particularly applicable to mine cars and will accordingly be described in such association and with reference to the accompanying drawings in which

Figure 1 is a plan view, partly in horizontal section of a typical embodiment of the invention;

Figure 2 is a view substantially on line 2—2 of Figure 1;

Figure 3 is a section substantially on line 3—3 of Figure 1;

Figure 4 is a section substantially on line 4—4 of Figure 1; and

Figure 5 is a section substantially on line 5—5 of Figure 1, being also a vertical section through the front portion of a mine car body with which the gearing is shown as being associated in novel manner.

Referring to the drawings, reference numeral 10 designates generally draft and buffer supporting means in the form, as here shown, of a bracket or housing designed as an end sill member and comprising a rear vertical wall 11 having cast integral therewith, as here shown, parallel upper and lower forwardly projecting webs or walls 12 and 13. Also cast integral, as here shown, with the rear wall 11, are a pair of arms 14 and 15 which have parallel outer vertical faces adapted to be riveted against sill members such as are indicated in dotted lines at 16 and 17. The rear wall 11 projects slightly outwardly of arms 14 and 15, these projecting portions being designated by the reference characters 18 and 19, respectively. The outer ends of walls 12 and 13 are joined by parallel walls 20 and 21 which integrally connect walls 11, 12 and 13. The rear wall 11 may be connected with arms 14 and 15 by means of gussets as at 22, Figures 1 and 4.

Walls 11 and 12 are curved forwardly and inwardly beyond the outer extremities of walls 20 and 21 and wall 12 has a relatively large central cutout or recess 23 which in effect divides the wall into two sections. Centrally, wall 13 is downwardly offset as at 24, Figures 2, 3 and 5, the offset 24 having a horizontal top face which extends up to a lower vertical attachment flange 25. The top wall 12 has a similar vertical attachment flange 26, the rear faces of flanges 25 and 26 lying in the same vertical plane as here shown.

The rear wall 11 is centrally rearwardly offset to form a triangular housing portion or pocket 27, the pocket portion being angular in plan view

and symmetrically disposed with reference to the bracket ends. The pocket is completed, top and bottom, by rearward extensions of walls 12 and 13.

Mounted in pocket 27 is a drawbar 28 which is substantially the shape of a flat isosceles triangle so as to be receivable in pocket 27 to seat firmly therein. The drawbar comprises top and bottom triangular webs 29 and 30 and an interconnecting vertical web 31. At its extremities, web 31 is in the plane of the forward edges of webs 29 and 30, but centrally it is rearwardly offset to provide a central pocket 32 whose rear wall is curved substantially concentrically with respect to aligned apertures 33 and 34 formed in webs 29 and 30 on a vertical line traversing the pocket. It will be noted from Figure 1 that the apex of the triangular drawbar is rounded off substantially on the curve of the vertical web 31 and that the point of pocket 27 is correspondingly curved.

The drawbar is slidably received between thickened portions 12' and 13' of walls 12 and 13. The rearward extensions of walls 12 and 13 are provided with vertically aligned fore and aft extending slots 35 and 36, Figures 1 and 5, which register with the apertures 33 and 34 in the drawbar, the latter being cylindrical and receiving a bolt 37 which projects upwardly and downwardly through slots 35 and 36. Washers 38 and 39 are interposed between the head of bolt 37 and a nut 40 screwed on the lower end of the bolt and retained by a cotter pin 41.

A draft hook 42 has a shank 43 extending between webs 29 and 30 of the drawbar into the pocket 32, the shank having an aperture in which bolt 37 is engaged. The hook has a heel portion 44 which is slidable on the upper surface of offset 24 which thus largely supports the weight of the hook. With the drawbar fully seated in recess 27, the end of the hook preferably does not extend outwardly beyond the forward limits of walls 12 and 13 so that danger of its injury through impact is thus avoided. The hook is rendered accessible for hitching purposes through recess 23 in the bracket top wall 12.

A pair of buffer elements 45 and 46 are supported between the outer ends of the bracket walls 12 and 13 for sliding movements, these buffer elements being interchangeable upon reversal. Each buffer element comprises parallel top and bottom walls 47 and 48, as most clearly shown in Figures 2 and 4, and, as most clearly shown in Figures 1 and 2, each comprises inner and outer parallel vertical end walls 49 and 50 which

connect the inner and outer edges of the top walls, all these walls preferably terminating rearwardly in the same vertical plane, the front edges of the walls being joined by a forward vertical wall 51 which adjacent wall 49 has a substantially flat impact face rounded off rearwardly to the outer wall 50. The top and bottom walls of the buffer elements are provided with fore and aft extending aligned slots 52 and 53 in which are engaged pins 54. The lower bracket wall 13 is provided with downward offsets 55 in which are provided upwardly open recesses receiving the lower ends of pins 54. The upper ends of pins 54 are received in apertures provided in wall 12 above the recesses and extending into upstanding bosses or collars 57 provided with counter bores as at 58, Figure 2, through which are passed cotter pins 59, these latter passing also through bores in the upper ends of pins 54. The bosses may be cut away to accommodate the ends of the cotter pins in the manner shown in Figure 2, and if desired, wedges 60 for opening the ends of the pins upon their insertion may be formed or secured on wall 12.

At each side of the slots 52 and 53 of each buffer element, spring seats 61 and 62 are formed on the inner face of front wall 51, Figures 1 and 4, these seats having centering bosses formed thereon. The drawbar is provided at its ends, that is, at the ends of vertical web 31, with centering bosses 63, Figure 1, the ends of the drawbar extending between the adjacent sides of the buffer elements so that bosses 63 are aligned with the seats 61 of the buffer elements. The rear wall 35 of the bracket is provided with centering bosses 64 aligned with seats 62. Inner compression springs 65 are interposed between the ends of the drawbar and seats 61, outer compression springs 66 being interposed between the bracket and seats 62.

It will be noted from Figure 1 that seats 61 are somewhat farther forward than seats 62, this being for the reason that, as here shown, the forward faces of the ends of the drawbar are in advance of the forward faces at the ends of bracket wall 11.

This enables springs 65 and 66 to be made interchangeable, since each has the same length as the other. As here shown, the springs are shown as being spaced at equal distances at the sides of pins 54 so that, being of equal strength, they exert a balanced effect upon the buffer elements.

The inner side walls of the buffer elements are guided to some extent by the shoulders formed by the thickened wall portions 12' and 13', the outer side walls of the buffer elements being disposed inwardly of the bracket side walls 20 and 21. The relation is such, however, as to permit pivoting of the buffer elements about pins 54, as well as movements toward and away from the bracket permitted by the slots 52 and 53. Outward movement of the buffer elements is limited by the engagement of the rear ends of slots 52 and 53 with the pins 54. Inward movement is limited by engagement of the inner walls 49 of the buffer elements with the ends of the drawbar and upon the simultaneous engagement, in the case of translational movement, of the outer walls 50 with lugs 67 and 68 formed in the corners between bracket wall portions 18 and 20, and 19 and 21.

In Figure 5, I have shown the gearing associated with one end of a mine car body 69. In this figure, reference numeral 70 designates one 75 of a pair of longitudinal sill members which may

be angle bars to the inner faces of which the bracket arms are riveted. A floor plate 71 is secured to the sill members as are also flare plates as at 72. The car end wall is constituted by an end plate 73 and the vertical web 74 of an angle bar 75 which constitutes an end sill member. The lower edge of plate 73 is sufficiently spaced from the top of web 74 to provide an opening 76 which extends from sill to sill and is adapted to receive the drawbar housing portion of bracket 10, 10 flange 25 being secured to the outer margin of web 74 and flange 26 being similarly secured to plate 73 so that opening 76 is entirely filled. In this manner, the outward projection of the gearing is considerably curtailed and a rigid end structure is provided. Reference numeral 77 designates a portion of a body side wall.

Upon the application of draft to the drawbar, as through hook 42 or any similar draft element, the drawbar tends to move forwardly out of pocket 27, thus compressing springs 65 which react to compress springs 66 by reason of the pivotal mounting of the buffer elements. The drawbar is guided against lateral displacement through the engagement of bolt 37 in slots 35 and 36, 25 forward outward movement of the drawbar being limited through engagement of bolt 27 with the outer ends of the slots. In order to prevent the entrance of material into the slots, washers 38 and 39 are of sufficient size to cover the slots 30 in all positions of bolt 37 therein. Preferably, the slots permit the drawbar to seat firmly against the rear bracket wall under the force of the springs.

While it will be seen that the springs act in 35 series under draft, it will be evident that they act in parallel under impact, reference being had to the springs associated with each buffer element. Under impact, the buffer elements may move translationally or may also pivot about pins 54 40 so that a very flexible action is assured.

While I have described a specific embodiment of my invention, it will be understood that the described construction may be varied considerably without departure from the invention as defined in the following claims.

I claim:

1. Apparatus of the class described comprising a bracket, a pair of buffer elements supported at horizontally opposite ends of the bracket for limited movement toward and away from the bracket and pivoting movements relative thereto on vertical axes, a rigid drawbar adapted for draft application at its central portion supported by the bracket with its ends behind the adjacent sides of said buffer elements, shock absorbing means between the ends of the drawbar and said adjacent sides of said buffer elements, and shock absorbing means between the outer sides of said buffer elements and abutments on the bracket, 60 the shock absorbing means associated with each buffer element being on opposite sides of the pivoting axis thereof and exerting a normally balanced action thereon, draft applied to the drawbar causing pivoting of said buffer elements and compression in series of the springs associated with each buffer element, the springs associated with each buffer element acting in parallel under buff.

2. Apparatus of the class described comprising 70 a bracket, a pair of buffer elements supported at horizontally opposite ends of the bracket for limited movement toward and away from the bracket and pivoting movements relative thereto on vertical axes, a rigid drawbar adapted for 75

draft application at its central portion supported by the bracket with its ends behind the adjacent sides of said buffer elements, guide means preventing lateral displacement of said drawbar, 5 shock absorbing means between the ends of the drawbar and said adjacent sides of said buffer elements, and shock absorbing means between the outer sides of said buffer elements and abutments on the bracket, the shock absorbing means 10 associated with each buffer element being on opposite sides of the pivoting axis thereof and exerting a normally balanced action thereon, draft applied to the draw bar causing pivoting of said buffer elements and compression in series of 15 the springs associated with each buffer element, the springs associated with each buffer element acting in parallel under buff.

3. Apparatus of the class described comprising a bracket, a pair of buffer elements supported at horizontally opposite ends of the bracket for limited movement toward and away from the bracket and pivoting movements relative thereto on vertical axes, a rigid drawbar adapted for draft application at its central portion supported by the bracket with its ends behind the adjacent sides of said buffer elements, a vertical bolt passed through said drawbar and slidably engaged with said bracket for preventing lateral displacement of said drawbar, shock absorbing means between 20 the ends of the drawbar and said adjacent sides of said buffer elements, and shock absorbing means between the outer sides of said buffer elements and abutments on the bracket, the shock absorbing means associated with each buffer element being on opposite sides of the pivoting axis thereof and exerting a normally balanced action thereon, draft applied to the draw bar causing pivoting of said buffer elements and compression in series of the springs associated with each 25 buffer element, the springs associated with each buffer element acting in parallel under buff.

4. Apparatus of the class described comprising a bracket, a pair of buffer elements supported at horizontally opposite ends of the bracket for limited movement toward and away from the bracket and pivoting movements relative thereto on vertical axes, a rigid drawbar supported by the bracket with its ends behind the adjacent sides of said buffer elements, a vertical bolt passed through the central portion of said drawbar and slidably engaged with said bracket for preventing lateral displacement of said drawbar, a draft element engaged with said bolt, shock absorbing means between the ends of the drawbar and said adjacent sides of said buffer elements, and shock absorbing means between the outer sides of said buffer elements and abutments on the bracket, the shock absorbing means associated with each buffer element being on opposite sides of the pivoting axis thereof and exerting a normally balanced action thereon, draft applied to the draw bar causing pivoting of said buffer elements and compression in series of the springs associated with each buffer element, the springs associated 30 with each buffer element acting in parallel under buff.

5. Apparatus of the class described comprising a bracket, a pair of buffer elements supported at horizontally opposite ends of the bracket for limited movement toward and away from the bracket and pivoting movements relative thereto on vertical axes, a rigid drawbar adapted for draft application at its central portion supported by the bracket with its ends behind the adjacent sides 35 of said buffer elements, said bracket including

top and bottom walls between which the drawbar is received, said walls being provided with aligned fore and aft extending slots, a bolt passed through the drawbar with its ends slidable in said slots for preventing lateral displacement of said drawbar, shock absorbing means between the ends of the drawbar and said adjacent sides of said buffer elements, and shock absorbing means between the outer sides of said buffer elements and abutments on the bracket, the shock absorbing means 40 associated with each buffer element being on opposite sides of the pivoting axis thereof and exerting a normally balanced action thereon, draft applied to the draw bar causing pivoting of said buffer elements and compression in series of the springs associated with each buffer element, the springs associated with each buffer element acting in parallel under buff.

6. Apparatus of the class described comprising a bracket, a pair of buffer elements supported at horizontally opposite ends of the bracket for limited movement toward and away from the bracket and pivoting movements relative thereto on vertical axes, a rigid drawbar supported by the bracket with its ends behind the adjacent sides of said buffer elements, said bracket including top and bottom walls between which the drawbar is received, said walls being provided with aligned fore and aft extending slots, a bolt passed through the drawbar with its ends slidable in said slots for preventing lateral displacement of said drawbar, a draft element engaged with said bolt, shock absorbing means between the ends of the drawbar and said adjacent sides of said buffer elements, and shock absorbing means between the outer sides of said buffer elements and abutments on the bracket, the shock absorbing means associated with each buffer element being on opposite sides of the pivoting axis thereof and exerting a normally balanced action thereon, draft applied to the draw bar causing pivoting of said buffer elements and compression in series of the springs associated with each buffer element, the springs associated with each buffer element acting in 45 parallel under buff.

7. Apparatus of the class described comprising a bracket, a pair of buffer elements supported at horizontally opposite ends of the bracket for limited movement toward and away from the bracket and pivoting movements relative thereto on vertical axes, a rigid drawbar supported by the bracket with its ends behind the adjacent sides of said buffer elements, said bracket including top and bottom walls between which the drawbar is received, said walls being provided with aligned fore and aft extending slots, a bolt passed through the drawbar with its ends slidable in said slots for preventing lateral displacement of said drawbar, the drawbar having a forwardly faced recess traversed by said bolt, a draft element extending into said recess and pivotally engaging said bolt, shock absorbing means between the ends of the drawbar and said adjacent sides of said buffer elements, and shock absorbing means between the outer sides of said buffer elements and abutments on the bracket, the shock absorbing means associated with each buffer element being on opposite sides of the pivoting axis thereof and exerting a normally balanced action thereon, draft applied to the drawbar causing pivoting of said buffer elements and compression in series of the springs associated with each buffer element, the springs associated with each buffer element acting in parallel under buff.

8. Apparatus of the class described comprising

a bracket, a pair of buffer elements supported at horizontally opposite ends of the bracket for limited movement toward and away from the bracket and pivoting movements relative thereto
5 on vertical axes, a rigid drawbar supported by the bracket with its ends behind the adjacent sides of said buffer elements, a vertical bolt passed through the central portion of said drawbar and slidably engaged with said bracket for preventing lateral displacement of said drawbar and for limiting movement of the drawbar away from the bracket, a draft element engaged with said bolt, shock absorbing means between the ends of the drawbar and said adjacent sides of said buffer
10 elements, and shock absorbing means between the outer sides of said buffer elements and abutments on the bracket, the shock absorbing means associated with each buffer element being on opposite sides of the pivoting axis thereof and exerting a normally balanced action thereon, draft applied to the drawbar causing pivoting of said buffer elements and compression in series of the springs associated with each buffer element, the springs associated with each buffer element acting in parallel under buff.

9. Apparatus of the class described comprising a bracket, a pair of buffer elements supported at horizontally opposite ends of the bracket for limited movement toward and away from the bracket and pivoting movements relative thereto on vertical axes, a rigid drawbar supported by the bracket with its ends behind the adjacent sides of said buffer elements, said bracket including top and bottom walls between which the drawbar is received, said walls being provided with aligned fore and aft extending slots, a bolt passed through the drawbar with its ends slidably in said slots for preventing lateral displacement of said drawbar and for limiting movement of the drawbar away from the bracket, a draft element engaged with said bolt, shock absorbing means between the ends of the drawbar and said adjacent sides of said buffer elements, and shock absorbing means between the outer sides of said buffer elements and abutments on the bracket, the shock absorbing means associated with each buffer element being on opposite sides of the pivoting axis thereof and exerting a normally balanced action thereon, draft applied to the drawbar causing pivoting of said buffer elements and compression in series of the springs associated with each buffer element, the springs associated with each buffer element acting in parallel under buff.

10. Apparatus of the class described comprising a bracket, a pair of buffer elements supported at horizontally opposite ends of the bracket for limited movement toward and away from the bracket and pivoting movements relative thereto on vertical axes, a rigid drawbar of substantially the

shape of a flat isosceles triangle with its apex rearwardly directed, said drawbar being supported by the bracket and the latter having an angular pocket in which the drawbar is normally seated and whereby movement of the drawbar toward the bracket is limited, the ends of said drawbar being positioned behind the adjacent sides of said buffer elements, shock absorbing means between the ends of the drawbar and said adjacent sides of said buffer elements, and shock absorbing means between the outer sides of said buffer elements and abutments on the bracket, the shock absorbing means associated with each buffer element being on opposite sides of the pivoting axis thereof and exerting a normally balanced action thereon, draft applied to the draw bar causing pivoting of said buffer elements and compression in series of the springs associated with each buffer element, the springs associated with each buffer element acting in parallel under buff.

11. For use in apparatus of the class described, a drawbar of substantially the shape of a flattened isosceles triangle, said drawbar having top and bottom triangular webs and a vertical web connecting said first-named webs substantially from end to end of the latter, said vertical web being centrally offset toward the apex of the triangle to provide a forwardly faced recess, said first-named webs being provided with apertures aligned on a line passing through said recess.

12. For use in apparatus of the class described, a drawbar of substantially the shape of a flattened isosceles triangle, said drawbar having top and bottom triangular webs and a vertical web connecting said first-named webs substantially from end to end of the latter, said vertical web being centrally offset toward the apex of the triangle to provide a forwardly faced recess, said first-named webs being provided with apertures aligned on a line passing through said recess, the extremities of said vertical web being substantially flush with the forward edges of said top and bottom webs, and spring centering bosses on the forward faces of said extremities.

13. The combination with a car body comprising end and side walls and a bottom wall, one of said end walls being provided with a horizontally elongated opening, of a draft and buffer means supporting bracket including a housing portion projecting inwardly of the body through said opening, means closing said opening in conjunction with said housing portion, said housing portion having top and bottom walls provided with aligned slots extending in the longitudinal direction of the body, a bolt slidably in said slots, and a washer on said bolt above said top wall of a size to cover the slot in said top wall in all sliding positions of said bolt.

GLENN E. EDMUND.
